Inventor
J. F. Crowley.

By

W. H. Sanders, Attorney.

UNITED STATES PATENT OFFICE.

JAMES F. CROWLEY, OF CHARITON, IOWA, ASSIGNOR OF TWO-FIFTHS TO H. B. BLANCHARD, OF CHARITON, IOWA.

DESIGN FOR A SIGN.

50,441.

Specification for Design.

Patented Mar. 13, 1917.

Application filed December 27, 1916. Serial No. 139,219. Term of patent 7 years.

To all whom it may concern:

Be it known that I, JAMES F. CROWLEY, a citizen of the United States, residing at Chariton, in the county of Lucas and State of Iowa, have invented a new, original, and ornamental Design for a Sign, of which the following is a specification, reference being had to the accompanying drawing, forming a part thereof.

The figure is a perspective view of my sign.

I claim:

The ornamental design for a sign, as shown.

JAMES F. CROWLEY.

Witnesses:

CHARLES S. FAIL,
HARVEY SWANSON.
